UNITED STATES PATENT OFFICE.

WILLIAM W. MACFARLANE, OF ELMINS PARK, PENNSYLVANIA, ASSIGNOR TO MACFARLANE COMMUNICATIONS CORPORATION, OF NEW YORK, N. Y., A CORPORATION OF DELAWARE.

TRAIN-CONTROL SYSTEM.

Continuation of application Serial No. 867,316, filed October 19, 1914. This application filed March 8, 1916, Serial No. 82,861. Renewed March 10, 1919. Serial No. 281,816.

To all whom it may concern:

Be it known that I, WILLIAM W. MACFARLANE, a citizen of the United States, and a resident of Elkins Park, in the county of 5 Montgomery and State of Pennsylvania, have invented certain new and useful Improvements in Train-Control Systems, of which the following is a specification.

This invention relates to railway signaling and more especially to signaling systems in which train-carried controlling devices are automatically controlled by track conditions and is a continuation of application Serial No. 867,316, filed Oct. 19, 1914. 10 The principal object of the invention is to provide a simplified method for utilizing the track circuit to continuously control a moving train without the use of ramp rails or continuous contact rails other than the traffic rails themselves.

This invention consists essentially of a train-carried controlling device held in continuous bridging contact with the track rails and having a sufficiently low resistance 15 to practically short-circuit the adjacent wheels and axles and utilize substantially the entire track-circuit current flow from rail to rail, to control the train. By this simple expedient the ramp rails with their 20 connecting control wires, and the continuous contact rails, of prior devices are done away with and at the same time a continuous control of a moving train is provided. Other features of the invention will be referred to 25 as the specification proceeds.

The invention will be hereinafter fully set forth in a preferred embodiment, and particularly pointed out in the claims.

In the drawings:

40 Fig. 1 is a plan view, partly in section, showing the contact shoes and the low resistance relay.

Fig. 2 is a side elevation, partly in section, of the parts shown in Fig. 1.

45 Fig. 3 is a view showing a detail of the low resistance relay.

Fig. 4 is an end view in section of the parts shown in Fig. 3.

50 Fig. 5 is a diagrammatic view of the low resistance relay shown in bridging relation with the rails.

Fig. 6 is a general diagrammatic view of

a track circuit adapted to be used with the devices of Figs. 1 to 5 inclusive.

Like reference characters designate like 55 parts in the several views.

In the drawings 1 designates a train-carried translating device which is arranged in continuous bridging engagement with, so as to be continuously responsive to, current 60 flowing in the track rails 2 and 3. In order to insure that sufficient current will be diverted from the path formed by the wheels and axles to flow from rail to rail through the translating device to cause the operation 65 of train controlling means, the translating device is constructed to offer an extremely low resistance to the passage of current therethrough.

The translating device 1 consists of a 70 helical strip 4 of copper, or other highly conductive material, having a considerable cross-sectional area as shown in Figures 13 and 14 and is preferably produced by helically cutting a solid bar of copper. Attached to the ends of the coil 4 by means of the clamps 5 are the copper cables 6 which lead to and are embedded in the contact shoes 7.

The contact shoes 7 preferably have a grid 80 formation as is shown in Figures 1 and 2, and have a steel base, or main portion 8, and an upper portion 10 of copper which is cast about the cable 6 and into the slots 9 of the base 8 so as to make contact with a large area of the track rail surface. By this construction a contact shoe is provided which combines the high conductivity 85 characteristic of copper with the wear resisting qualities of steel. The combined re-

sistance of the contact shoes 7, the copper cables 6, and the copper coil 4 is so low as to virtually short-circuit the adjacent wheels and axles of the vehicle. So marked is this difference in the resistance values between the current path through the coil 4 and the current path from rail to rail through the wheels and axles of the vehicle that, in the preferred embodiment of the device, the contact shoes are placed just to the rear of the forward driving wheels of the locomotive. Notwithstanding the fact that there are a plurality of wheels and axles between the contact shoes and the

source of current in this situation, the resistance value of the translating device can be made so low that no appreciable shunting effect on the part of such wheels and axles is apparent, and sufficient current is available to control the polarized relay 1 in the path between the contact shoes. This resistance value can also be readily adjusted so that an additional axle, such as that of another vehicle, placed across the track rails between the translating device and track battery will be sufficient to shunt the translating device. By placing the contact shoes to the rear of a driving wheel, a cleared rail surface is insured with which the contact shoes can engage.

The contact shoes are provided at the ends with the lugs 11 to which are connected the eye bolts 12 engaging the downwardly extending pins 13 and held in place by means of cotter pins, or the like, 14^a. The shoes are normally pressed into close engagement with the track rails through the action of the springs 14 which carry the inverted U-shaped guide members 15 at their lower ends. The guide members 15 not only bear downwardly on the contact shoes but they serve to hold the shoes against movement transversely to the rails.

To serve as a warning of the breaking of a contact shoe from its fastenings while the vehicle is in motion, a connection such as the wire, or cable 16, may be provided between the contact shoes and a valve 17 in the train pipe 18. It will be evident that, assuming the vehicle is moving to the right in Figure 2, upon a breaking or uncoupling of the eye bolts 12, for instance, the movement of the shoe to the left relatively to the movement of the train would pull on the wire 16 to open the valve 17 and vent the train pipe 18 to set the brakes and stop the train. Each contact shoe, or each end of each contact shoe, may be equipped with a safety device such as the one just described.

The coil 4 is mounted in a casing 19, preferably of wood, and is provided with a soft iron core 20 separated from the coil by a suitable insulating shell 21. The ends of the core are provided with polarized armatures 22 and 23 suitably pivoted at 24 and adapted to be swung into engagement with contact plates 25 and 26 when the armatures are attracted by the adjacent poles of the core 20. Stops 27 are provided against which the armatures are biased by gravity to engage when they are in unattracted condition.

It will be seen that the coil 4, the core 20 and the armatures 22 and 23 form a polarized relay which is responsive to changes in the characteristic of the current flowing in the track rails and to the presence or absence of current in the track rails as

well. The changes in the characteristic of the track circuit are preferably produced by changing the polarity of a direct current but such changes may be produced in various other ways, such as by changing the phase or frequency of an alternating current.

When current flows through the coil 4 in a certain direction, say from the track rail 3 to the track rail 2, the soft iron core 20 is given such a polarity that the armature 23 is attracted and moved into engagement with the contact member 26, while the other armature 22 is not only repelled by the adjacent pole of the core 20 but it is also urged by gravity out of engagement with the contact piece 25 and into engagement with the stop 27. When current flows through the coil in the opposite direction, that is from track rail 2 to track rail 3, the armature 22 is attracted so that it will move into engagement with the contact member 25 and at the same time the armature 23 will break contact with the contact member 26. When no current is flowing through the coil 4 both armatures 22 and 23 move out of engagement with their respective contacts.

We thus have three conditions of the polarized relay 1 which are made to correspond to the three traffic conditions, safety, caution, and danger. Under safety traffic conditions the armature 23 is caused to make contact with the contact member 26 while the armature 22 is moved away from the contact 25. Under caution conditions the armature 22 is attracted and moved into contact with the contact member 25 while the armature 23 is moved out of engagement with the contact member 26. Under danger conditions both armatures will leave their respective contacts.

In order to control the operation of the low resistance relay a track circuit system such as is illustrated in Figure 6 of the drawings may be used. The particular arrangement of circuits shown, however, is intended only for an example and it is to be understood that other and various arrangements may be employed such as will best fit the conditions of different installations.

The track rails 2 and 3 are divided into suitable block sections A, B, C, D and E which are insulated from each other in the usual manner. Each block is provided at the exit end with a source of current 28 normally connected through the conductor 29, contacts 30, conductor 31, and conductor 32, to the track rail 3, and through the conductor 33 including the resistance 34, and conductor 35, to the track rail 2. The source of current is designed to furnish the ordinary low voltage current to the track rail circuit but preferably differs from

the ordinary track source heretofore used in that it is arranged to furnish a current of comparatively large volume relatively to that supplied by the usual track battery.

5 The track circuit is normally completed through the conductor 36 leading from the track rail 3 at the entrance end of the block, the pole-changing relay 37, and conductor 38, connected in turn to track rail 2. A 10 circuit-controlling relay 39 is connected by the branch conductors 40 and 41 to the conductors 36 and 38 respectively so that the two relays 37 and 39 are arranged in a parallel relation to each other. The relay 37 has a high resistance value while 15 the relay 39 has a relatively low resistance so that for certain values of the track current the circuit-controlling relay 39 can be energized without energizing the pole-changing relay 37.

The circuit-controlling relay 39 in its energized condition actuates the circuit closer 42 to bridge the contacts 30 and close a break in the normal or primary track circuit already described. In the deenergized condition of the relay 39 the circuit closer 42 breaks contact with the contacts 30 and moves into bridging engagement with the contacts 43 to close a circuit in a secondary, 20 or substitute track circuit which may be traced as follows: current source 28, conductor 29, contacts 43, conductor 44, resistance 45, track rail 2, conductor 38, conductor 41, relay 39, conductor 40, conductor 36, track rail 3, conductor 32, conductor 46, conductor 33, and resistance 34 back to battery. The inclusion of the two resistances 34 and 45 in series in this circuit so affects the value of the current that the high resistance relay 37 25 remains deenergized while the low resistance relay 39 is energized to actuate the circuit closer 42.

The pole-changing relay 37 in its energized condition, brings the armature 47 into engagement with the contacts 48 and 49. This serves to connect the conductors 31—32 and 35—33 respectively which form part of the normal, or primary, track circuit already referred to. In the deenergized condition of this relay the armature 47 engages the contacts 50 and 51. This serves to connect the conductors 52—35 and 32—46 and, when the relay 39 is energized to bridge the contacts 30, establishes a caution circuit as follows: current source 28, conductor 29, contacts 30, conductor 31, conductor 52, armature 47, conductor 35, track rail 2, conductor 38, relays 37 and 39, conductor 36, track rail 3, conductor 32, armature 47, conductor 46, conductor 33, resistance 34, and back to battery.

The presence of a train, indicated at 53 in block section B, will short-circuit the relays 37 and 39 connected to the rails of block B 65 which will result in breaking the normal

track circuit and establish the secondary circuit in block C as has been already explained. This circuit in block section C will energize the magnet 39 to bridge the contacts 30 in the normal track circuit of block section D. 70 However, the deenergization of the pole changing relay 37 connected to the rails 2 and 3 serves to reverse the polarity of the track rails in this section so that while the current has the same value that it has in 75 normal conditions, it will tend to flow from rail 2 to rail 3, instead of from rail 3 to rail 2, as is the case under wholly normal conditions.

What is claimed, is:

1. A system of train control comprising: traffic tracks divided into blocks, a track circuit, for each block, normally closed through the rails of the block, a car, a current path on the car the resistance of which is lower than the resistance of the wheels and axles of the car and through which the track current passes when the car occupies a block, a translating device in said low resistance path continuously responsive to variations in the characteristic of the current of the track circuit, and means for varying the characteristic of the current of the track circuit. 80

2. A system of train control comprising: traffic tracks divided into blocks, a track circuit, for each block, normally closed through the rails of the block with current having a certain characteristic, a car, a current path on the car the resistance of which is lower than the resistance of the wheels and axles of the car and through which the track current passes when the car occupies a block, and a translating device in said low resistance path continuously responsive to 90 variations in the characteristic or the continuity of the track current. 95

3. A system of train control comprising: a traffic track, a track circuit including a relatively low voltage source capacitated to 100 deliver a relatively large volume of current and including sufficient resistance to normally prevent the flow of a large volume of current, a train having a path of sufficiently low resistance to short-circuit a part of the resistance normally in the track circuit and to permit a relatively large volume of current to flow, and a translating device under the influence of said low resistance path adapted to utilize a current having a relatively low voltage but requiring a current having a relatively large volume. 110

4. A system of traffic control comprising: a traffic track, a track circuit including a source of current adapted to produce a current of low voltage and relatively large volume, a resistance in said track circuit, a train, and a conductor carried by said train arranged to bridge said rails and short-circuit the resistance in said track circuit, 125 130

whereby a current of large volume will flow through said low resistance conductor.

5. A system of train control comprising: traffic rails divided by insulation into conducting blocks, a low voltage source of electricity capable of delivering a large volume of current connecting said rails, a resistance connecting said rails, a train, a low resistance train controlling path on said train 10 through which the circuit is diverted from said track resistance when the train enters a block, whereby a current of large volume passes through the low resistance path, and whereby a current of low volume normally 15 flows through the track circuit when a train is not in the block.

6. A system of train control comprising: a traffic track, a train having a plurality of connected pairs of traffic wheels traveling 20 on opposite rails of the traffic track forming parallel paths from one rail to the opposite rail, a track circuit including the rails of the traffic track, a low-voltage battery in said track circuit, a low resistance path on 25 the train extending from one rail to the opposite rail and capacitated to conduct a large volume of current to the practical exclusion of the remaining parallel paths by reason of the low resistance of said path, a 30 resistance element in said track circuit adapted to be short-circuited by the train, a translating device forming a part of the low-resistance path and adapted to be actuated by a low-voltage current, regardless of the drop in potential between the 35 low resistance path and adjacent parallel paths.

7. A system of traffic control comprising: traffic rails, a track circuit normally closed 40 through said rails, a source of current for said circuit, a high resistance in said circuit, a train carrying a low resistance conductor arranged to bridge said rails and short-circuit the adjacent wheels and axles and the 45 high resistance in said track circuit whereby a current of large volume flows through said low resistance conductor, and a translating device under the influence of said low resistance conductor.

50 8. A system of train control comprising: traffic rails divided into blocks by insulation, a track circuit normally closed through the rails of each block, a resistance in each circuit whereby a current of small volume normally 55 flows through said circuit, a car, a current path on the car the resistance of which is lower than the resistance of the axles of the car and through which the track current passes from rail to rail when the car enters a block to shunt said resistance and permit a large volume of current to flow, and a translating device in said low resistance.

60 9. A system of train control comprising:

a track circuit including a low voltage 65 source of relatively large volume, a train, a translating device on the train having a low resistance and provided with a number of ampere turns sufficient to create a relatively powerful magnetic field with a low voltage 70 current of relatively large volume, and means for supplying current from said track circuit to said translating device.

10. A system of traffic control comprising: 75 a train, traffic rails, a track circuit having a source adapted to supply a comparatively large volume of current to said rails, a translating device on the train offering a sufficiently low resistance to permit a relatively large volume of current to flow 80 therethrough and providing a sufficient number of ampere turns to create a relatively powerful magnetic field, and means for supplying a sufficient volume of current from said rails to operate said translating device. 85

11. A system of traffic control comprising: 90 a train, traffic rails, a source of current arranged to supply current to said rails, and a translating device on the train having a sufficiently low resistance to permit a relatively large volume of current to flow therethrough and providing a sufficient number of ampere turns to create a relatively powerful magnetic field, said translating device being placed in a current path 95 in shunt with other current paths available to conduct current from rail to rail across the train, said source of current being adapted to deliver current to said rails having a volume such that the proportionate 100 volume of current supplied to the shunt path on the train is sufficient to operate the translating device therein.

12. A system of traffic control comprising: 105 a train, traffic rails, a low-voltage source of current arranged to supply current to said rails, and a translating device on the train having a sufficiently low resistance to permit a relatively large volume of current to flow therethrough and providing a sufficient number of ampere turns to create a relatively powerful magnetic field, said translating device being placed in a current path 110 in shunt with other current paths available to conduct current from rail to rail across the train, said source of current being adapted to deliver current to said rails having a volume such that the proportionate 115 volume of current supplied to the shunt path on the train is sufficient to operate the translating device therein.

Signed at Philadelphia in the county of Philadelphia and State of Pennsylvania this 6th day of March A. D. 1916.
